SUCTION CLEANER

Bernard C. Becker, Canton, Ohio, assignor to The Hoover Company, North Canton, Ohio, a corporation of Ohio

Application April 9, 1934, Serial No. 719,703

16 Claims. (Cl. 21—127)

The present invention relates to suction cleaners in general and particularly to new and novel improvements in suction cleaner odorizer units. More specifically the invention comprises an odorizer unit which is built into the cleaner and which includes valve means which function to control the flow of air past a redolent volatile medium.

It is an object of the invention to provide a new and improved odorizer unit in a suction cleaner. It is another object of the invention to provide an odorizer unit which is manually controllable. Still another object is a provision, in a suction cleaner, of a new and improved manually controllable odorizer unit, in which clean air passes a volatile substance and thereafter enters the main air stream through the cleaner. A still further object is the provision, in a suction cleaner, of an improved odorizer unit including valve means which are manually operable and which seal the volatile element from atmosphere to prevent unintended vaporization when the cleaner is not in use. Still another object is the provision, as an accessory for a suction cleaner, of an odorizer unit which includes a replaceable redolent volatile element which is opened to a stream of air by a manually controllable valve, which valve also functions to interrupt the air stream and seal the element. These and other more specific objects will appear upon reading the following specifications and claims, and upon considering in connection therewith the attached drawings to which they relate.

Referring now to the drawings in which the same reference characters refer to the same parts throughout:

Figure 1 is a side elevation of a modern suction cleaner embodying the present invention with certain parts broken away;

Figure 2 is a bottom view of the removable odorizer and pulley housing unit constructed in accordance with the present invention;

Figure 3 is a side view of the unit shown in Figure 2;

Figure 4 is a view of the opposite side of the element shown in Figure 2;

Figure 5 is a partial section through the cleaner embodying the odorizer unit, being a section upon the line 5—5 of Figure 2;

Figure 6 is a partial section through the odorizer unit upon the line 6—6 of Figure 4;

Figure 7 is a section through the manually controllable valve upon the line 7—7 of Figure 6;

Figure 8 is a section upon the line 8—8 of Fig-

ure 6, illustrating the secondary air passageway and the control valve;

Figure 9 is section similar to Figure 8 but with a control valve in the "off" position;

Figure 10 is a top view of the odorizer unit in a disassembled or exploded relationship.

In the operation of an efficient suction cleaner foreign matter of many types is removed from the article undergoing cleaning. This matter is carried through the cleaner proper by the moving air stream and exhausted into the cleaner dust bag where the foreign matter is removed and the air passes through the filtering medium to the exterior atmosphere. Modern dust bags are highly efficient and remove practically all of the suspended foreign matter from the air. There is, however, a very small percentage of fine foreign matter which leaks through the filtering fabric and is objectionable as it is light and easily carried by the air and becomes noticeable to the user through coming into contact with his nostrils. The user may sense a slight odor of dust as a result.

In a suction cleaner constructed in accordance with the present invention an odorizer unit is embodied in the machine and causes a moving stream of 'clean' air to pass over a volatile substance. Certain of the volatile substance evaporates into the air and is carried thereby into the cleaner dustbag, and passes therethrough into the surrounding atmosphere. This volatile element gives off a pleasant odor and shields the slight dust odor aforementioned. As the volatile substance is usually volatile at room temperatures it is desirable that it be sealed from the atmosphere when the machine is not in use, and to accomplish this purpose manually controlled valve means are provided in the present invention which open and close the air passageways leading to and from the substance which is otherwise sealed from atmosphere.

Referring now to Figure 1 in particular a modern suction cleaner is shown in which a main casing, including a nozzle 1, a fan casing 2, and an exhaust outlet 3, is movably supported upon the surface undergoing cleaning by means of front and rear wheels 4, 4 and 5, 5. A motor casing 6 is positioned immediately above the fan chamber 2 and the motor shaft 7 is extended downwardly through the fan chamber, where it carries the rotatable fan 8. The shaft 7 continues on through the fan chamber eye 9 and into the air passageway which connects the fan chamber to the interior of nozzle 1. Within this passageway the shaft is provided with a

pulley 10 which is engaged by an agitator-driving belt 11. The air passageway adjacent the fan chamber is completed by a removable pulley cover or housing member 12. The cleaner also includes a pivoted handle 13 by means of which the operator can exert a propelling force and, as in all suction cleaners of this type, a dust bag 14 is provided which is removably secured to the exhaust outlet 3 by means 15.

In the operation of this cleaner the closing of an unshown motor switch on the handle 13 causes electric current to pass through the driving motor positioned within casing 6 and the motor shaft 7 rotates carrying with it the suction-creating fan 8. The rotation of fan 8 creates a reduced pressure which draws cleaning air through the nozzle 1, past any agitating means which may be provided therein through the air passageway formed by housing 12, into fan chamber 2, and exhausts the air through the outlet 3 into bag 14. Substantially all the suspended foreign matter in the air is filtered therefrom as the air passes through the bag and into the exterior atmosphere.

According to the present invention the pulley cover or housing 12 is constructed integrally with an odorizer unit. The member is seen to comprise bottom and side walls which enclose the eye 9 of the fan chamber and mate with the air passageway opening in the nozzle 1. Forwardly-projecting lugs 18, 18 on the forward edges of the side walls of the unit are adapted to cooperate with correspondingly shaped sockets in the nozzle 1 to support the front end of the member. A rearwardly extending lug 19 is adapted to cooperate with a manually operable lock 20 to support the rear end. These cooperating means secure the unit in place on the cleaner proper and make possible its easy removal when necessary for the attachment of dusting tools to the eye 9 of the fan chamber or for the replacement of belt 11.

As is illustrated in Figure 6 unit 12 is provided with a transversely extending cylindrical bore or seat 22. A removable open ended vial or bottle 23 is positioned within seat 22 with its open end forced against a ring washer or seal 24 by a spring-pressed plunger construction 25 which is carried by a pivoted cap 26 adapted to overlie and close seat 22. To remove bottle 23 from its seat it is necessary only to manually depress a leaf spring latch 27 which normally overlies the in-turned edge of cap 26. Cap 26 can then be pivoted to let the bottle be withdrawn from its seat.

A valve chamber 28 opens into the inner end of seat 22 through the seal 24, being smaller in diameter than the open end of vial 23. As is shown in Figures 8 and 9 chamber 28 is connected to the atmosphere by an air passageway 29 and to a point of low pressure in the machine by a passageway 30 which leads to the interior of member 12. The two passageways 29 and 30, it is to be noted, are open to valve chamber 28 at circumferentially spaced points.

A rotatable valve 31 is positioned in chamber 28 and makes sealing contact with the enclosing walls thereof. Valve 31 is hollow and is formed with openings or ports 33 and 34 which are adapted to mate with passageways 29 and 30, respectively. The valve is also formed with a longitudinally extending wall or barrier 32 which divides the valve chamber into two parallel passageways leading from passageways 29 and 30 to the mouth of vial 23. The inner headed end of valve 31 is positioned within seat 22 and makes sealing contact with ring washer 24 which en-

closes it, the relationship being such that no air passes between the outer wall of valve 31 and the walls of valve chamber 28.

A stem 35 extends outwardly from valve 31 through a suitable bore 36 and is provided on its outer end with an enclosing cap 37 which is held in place by means of a screw 38. Casing 12 is counterbored at the end of bore 36 and a coiled spring 39 is provided which urges the valve outwardly and maintains the inner headed end thereof against its seat. Stem 35 is provided with a shoulder 40 which fits within an arcuate seat 41 in the casing 12. Seat 41 is of such extent that the valve may be rotated, by means of the cap 37 and stem 35, between the "on" and "off" positions illustrated respectively in Figures 8 and 9. In order that the user may be informed as to the relationship existing in the unit a marker 42 is placed on the casing inside the cap 37 which is provided with a cutaway portion 43 through which the marker is visible. The words "on" and "off," positioned at the ends of this cutaway section, are found positioned opposite the marker when the valve is positioned as shown in Figures 8 and 9, respectively.

The manually operable cap 37 at the end of valve 31 is positioned rearwardly of and at one side of the casing 12, as is clearly seen in Figure 6, in which position it is readily operated by the user with the machine positioned upon the floor. The parts are so related that the operator can see from his place above the machine whether the unit is in the "on" or in the "off" position by means of the marker 42.

The construction of the odorizer unit assembly is extremely simple. The vial 23 comprises a separately saleable unit which is replaceable when the volatile element has become exhausted. The bottle is so constructed that a removable cork or cap can seal the contents from the atmosphere when not positioned within the unit. In its preferred form the volatile substance is a liquid carried by a carrying medium in which capillary action moves more liquid to the mouth of the bottle as vaporization takes place. It is imperative that the volatile substance does not run out of the mouth of the bottle when the bottle is placed on its side as when in use.

The valve of the unit is assembled by inserting the valve element through the enlarged seat 22 which receives the bottle and passing it therethrough until the valve 31 seats within its chamber 28 at which time the stem 35 will be extended through the casing. A coil spring 39 surrounds the outer end of the stem and is held in place by the enclosing manually rotatable cap 37 which is itself secured to the stem by the screw 38. After the valve has been positioned at the time of construction it should not require further attention.

In the use of the invention air passes through the cleaner nozzle, the unit housing 12, into the fan chamber 2, and is exhausted into the dust bag 14. If the cap 37 is so positioned that the marker 42 is opposite the word "off" then the interior of bottle 23 is sealed by the valve 31 from the suction inlet of the fan chamber and from atmosphere, and air neither passes into nor out of the bottle. Upon the rotation of the cap 37 so that the word "on" is opposite the marker 42 the valve is rotated from the position shown in Figure 9 to that shown in Figure 8 and the ports 33 and 34 are open to the passageways 29 and 30. As passageway 30 is connected to a point of low pressure air is drawn

from the surrounding atmosphere, down the passageway 29, thru the port 33, thru the valve chamber to the mouth of the vial, back the other side of the valve chamber as defined by the barrier 32, and thru port 34 and passageway 30 and into the main air stream.

I claim:

1. In a suction cleaner including suction-creating means and a main cleaning air passageway connected to said means, an auxiliary fresh air passageway connected to said means, a receptacle for a volatile agent connected intermediate the ends of said auxiliary air passageway, a rotatable valve to seal said receptacle from said passageway, manually operable means to actuate said valve, and means to indicate the relationship of said valve.

2. In a suction cleaner including suction-creating means and a main cleaning air passageway connected to said means, an auxiliary fresh air passageway open to atmosphere and to said means, a removable receptacle for a volatile agent open to said auxiliary air passageway, means removably locking said receptacle in place, and valve means controlling the flow of air thru said auxiliary air passageway and adapted to seal said receptacle from atmosphere and from said suction-creating means.

3. In a suction cleaner including suction-creating means and a main cleaning air passageway connected to said means, an auxiliary fresh air passageway open to atmosphere and to said means, an open-ended removable receptacle for a volatile agent open to said auxiliary passageway to permit air circulation in said receptacle, a seal seating the periphery of the open mouth of said receptacle, and means resiliently urging said receptacle against said seal.

4. In a suction cleaner including suction-creating means and a main cleaning air passageway connected to said means, an auxiliary fresh air passageway open to atmosphere and to said means, an open-ended removable volatile-agent-containing receptacle open to said auxiliary passageway so that air will circulate therein, sealing means seating the open mouth of said receptacle to prevent air leakage into said receptacle or said auxiliary passageway, a removable member overlying the closed end of said receptacle, and resilient means carried by said removable member contacting and urging said receptacle against said seal.

5. In a suction cleaner including suction-creating means and a main cleaning air passageway connected to said means, an auxiliary clean air passageway open to atmosphere and to said means to convey a stream of air therebetween, an open-ended removable receptacle for a volatile agent open to said auxiliary passageway so that air will circulate therein, a seal seating the open mouth of said receptacle in sealed relationship to said passageway, and means retaining said receptacle in seating relationship with said seal.

6. In a suction cleaner including suction-creating means and a main cleaning air passageway connected to said means, an auxiliary clean air passageway open to atmosphere and to said means to convey a stream of air therebetween, an open-ended removable receptacle for a volatile agent open to said auxiliary passageway so that air will circulate therein, a seal seating the open mouth of said receptacle in sealed relationship to said passageway, a pivoted cover member overlying the closed end of said receptacle.

tacle, a spring latch securing said cover member in place, and resilient means carried by said cover member contacting and urging said receptacle against said seal.

5 7. In a suction cleaner including suction-creating means and a main cleaning air passageway connected to said means, an auxiliary clean air passageway connected to atmosphere and to said suction-creating means, said auxiliary passageway including a valve chamber, a closed volatile agent receptacle open to said auxiliary passageway at said valve chamber, and manually operable valve means in said chamber to open said auxiliary passageway to said receptacle or to seal 15 said receptacle from atmosphere and said suction-creating means.

8. In a suction cleaner including suction-creating means, an auxiliary air passageway connected to atmosphere and to said suction-creating 20 means, said auxiliary passageway including a valve chamber having an inlet and an outlet, a volatile agent receptacle open to the inlet and the outlet of said valve chamber, a manually rotatable valve in said chamber including means to 25 close the inlet and outlet of said chamber, and means to indicate the valve position.

9. In a suction cleaner including suction-creating means, an auxiliary air passageway connected to atmosphere and to said suction-creating 30 means, said auxiliary passageway including a valve chamber, a volatile agent receptacle open to said auxiliary passageway at said valve chamber, a rotatable valve including stops for the inlet and outlet of said chamber and a barrier, said 35 barrier dividing said chamber so that air passing therethru must travel the length of said barrier to the said receptacle, said valve also including a manually rotatable stem by which said valve may be controlled.

40 10. In a suction cleaner, a combination pulley-house-cover and odorizer unit comprising a body adapted to form a part of the air passageway between a nozzle and a fan chamber, said body provided exteriorly with a seat for a volatile agent 45 receptacle, means to releasably secure a receptacle in said seat, a chamber at one end of said seat and open thereto, means connecting said chamber to atmosphere and to the interior of said body, and a manually operable valve in said 50 chamber to control the flow of air therethru.

11. A vacuum cleaner including a casing having an inlet port and outlet port, means for producing flow of air through said casing, a hollow part integral with said casing and opening to 55 the interior of said casing, and a holding member for air conditioning material removably positioned within said hollow part, said hollow part and said holding member being disposed away from the center of the air stream through said 60 casing so as to provide for free flow of air through the casing, the opening of said hollow part to the interior of said casing being closable from outside said casing.

12. A vacuum cleaner including a casing 65 formed with an inlet port and an outlet port and including a removable cover member, means for producing flow of air through the space enclosed by said cover member, a hollow part integral with said cover member and opening to said 70 space, a holding member for air conditioning material removably positioned within said hollow part, and means accessible from outside said casing to close the opening of said hollow part to said space.

75 13. A vacuum cleaner including a casing

formed with an inlet port and an outlet port, means for producing flow of air through said casing, a hollow part integral with said casing, said hollow part opening to both the interior and exterior of said casing, and a holding member for air conditioning material insertable into said hollow part through the exterior opening, the interior opening being closable from outside said casing.

14. In a suction cleaner, suction-creating means, a main dirty air passageway connected to said means, a secondary clean air passageway including a portion passing a volatile agent connected to said means and to atmosphere to convey clean air from the latter to the former, valve means to seal said portion from the suction-creating means, valve means to seal said portion from atmosphere, and manually operable means to position said valve means.

15. In a suction cleaner, suction-creating means, a main dirty air passageway connected to

the suction side of said means, a secondary clean air passageway connected to atmosphere and to the suction side of said means, a receptacle for a volatile agent open to said secondary passageway intermediate its ends, valve means to seal said receptacle from atmosphere and from said suction-creating means, and manually operable means to position said valve means.

16. In a suction cleaner, suction-creating means, a dirty air passageway connected to said means, means to retain a body of volatile material adapted to volatilize at its surface, means forming a passageway to direct clean air from atmosphere into contact with the surface of a body held by said retaining means, means forming a passageway to convey air from said surface into said dirty air passageway on the suction side of said suction-creating means, and means to close off the flow of clean air in said passageways to and from said body.

BERNARD C. BECKER.
